UNITED STATES PATENT OFFICE

2,425,920

SINGLE-ACTING FLAT-BED WEB PERFECTING PRINTING PRESS

Paul F. Cox, Los Angeles, Calif.

Application April 6, 1944, Serial No. 529,785

15 Claims. (Cl. 101—257)

1

This invention is a novel printing press particularly adapted for use by the publishers of daily newspapers in small towns; and one object thereof is to produce a small inexpensive flat bed roll-fed web perfecting press which can compete in cost with the usual hand-fed cylinder presses which at present are the only presses available to the small daily and weekly publisher. Flat bed web presses have heretofore been produced, but there is a present tendency to increase the cost thereof owing to constantly added improvements to such extent that their initial low-cost feature has been for the most part lost.

Another object of the invention is to provide a single acting flat bed web perfecting press which can compete with the faster presses in which speed was the most important feature.

Another object of my invention is to provide a roll-fed web perfecting press that will produce the same quality of printing as any other press in its class, and more particularly will be within the cost range of the small publisher who is not so much interested in speed as in cost. Many small publishers are now using the hand-feed cut-sheet presses and are desirous of obtaining an inexpensive press that will put them into the roll-fed web press class which would permit them to perfect their daily, weekly, or other product in one single operation thus printing their editions at more than double the speed of their present hand-fed equipment. It is not the fault of the small publisher that he is unable to purchase a roll-fed web press suitable for his publication. He is in the market for such a press, but cannot be expected to purchase a press that is larger than necessary for his publication, nor can the press manufacturer sell him a press having twice the capacity of his needs. Few such publishers will pay more for a press than it is worth to him, though the press may have greater capacity than his needs.

Further objects of my invention are to provide a press which I prefer to call a "pendulum" press, because of its novel cylinder action and arrangement of parts, and in which old well-tried features of the flat bed web press type are arranged in a novel manner which will eliminate many idle rollers, cams, shafts, gears, and other elements which heretofore were necessary in presses of this type; also to provide in such presses a new arrangement of parts designed to economize floor space; said press comprising a single-acting flat bed web perfecting press having a travelling impression cylinder, a pair of pendulum swinging bars coacting with the impression cylinder, said bars being suspended from a horizontal shaft located above the printing couples, and being perpendicularly arranged and loosely pivoted at their upper ends on said shaft, their lower ends being loosely connected with the impression cyl-

2

inder journals, together with means for giving the bars a pendulum-like motion to and fro, whereby the impression cylinder may be moved forwards and backwards over the type bed; a pair of turning bars arranged directly above the impression cylinder and type bed directly above the printing couples, thereby reducing the length of the press at least four feet, and the pendulum construction permitting a further reduction in floor space; and a driven web feed roll adjacent the turning bars, whereby the advancing web is fed to the bars before the web is turned over, the same web feed roll receiving and advancing the web back to the impression cylinder after the web is turned over.

Still further objects of my invention are to provide a novel "Pendulum" press having a type-bed which is readily accessible to the operator permitting quick changes in pages or corrections in type forms which are so often necessary during press time; said press having an efficient linking system and distribution; also a press in which all rollers are interchangeable, three composition rollers only necessary to perfect a 4-page newspaper or an 8-page tabloid publication; also to provide a press which is so simple in construction that it will produce high quality printing owing to the fact that 90% of the web idle rollers are eliminated in my "pendulum" press; also a press which can be built with or without a folder; and in which colored posters can be printed, and if desired delivered flat, a feature not found in other flat bed newspaper presses.

A further essential feature and object of my invention is to provide a press of the above class so designed that the press may be shipped complete erected, thus saving the purchaser the expense of erection heretofore added on to the initial press cost, and which press will not require the provision of a pit upon arriving at its destination.

Other minor objects of the invention will be hereinafter set forth.

I will explain the invention with reference to the accompanying drawings which illustrate one practical embodiment thereof to enable others familiar with the art to adopt and use the same; and will summarize in the claims the novel features of construction and novel combinations of parts, for which protection is desired.

In said drawings—

Fig. 1 is an elevation of my press looking at the roll-feed end.

Fig. 2 is one side elevation thereof.

Fig. 3 is a side elevation thereof looking at the opposite side.

Fig. 4 is a top plan view of the machine shown in the preceding figures.

Fig. 5 is a vertical section on the line 5—5, 60 Fig. 1.

Fig. 6 is a vertical section on the line 6—6, Fig. 1.

Fig. 7 is a detail view showing the Geneva gear.

As shown, my novel flat-bed web perfecting press consists of a base 1 which is the stationary type bed, preferably of width to accommodate two widths of type forms and of the paper web side by side, said bed being accessibly disposed close to the floor for convenience of the operator. At opposite sides of bed 1 are uprights 2 and 3 respectively which are preferably rectangular in shape and open, and are connected together by means of angular bars 4 and 5, or the like, connecting the side frames 2 and 3 adjacent their upper ends.

Extending from the lower portion of frames 2 and 3 are extensions 2a and 3a respectively having downwardly directed slots 2b and 3b respectively receiving opposite ends of a shaft 6 upon which is mounted the roll of paper W which is to be fed into the press, the roll W being disposed upon shaft 6 opposite one-half of the width of base 1.

Disposed horizontally at the lower ends of side frames 2 and 3 above base 1 are slots 2c—3c respectively (Figs. 5 and 6) receiving sliding blocks 7 carrying eccentric journals for an impression cylinder 8 extending the full width of the bed and carrying a gear 8a at one end meshing with a rack 9 so as to cause rotation of cylinder 8 as the same is moved backwards and forwards across the type beds as hereinafter described, the eccentric bearings being actuated by an arm 8b cooperating with pins 10 and 11 (Fig. 2) on the side of frame 2 so that cylinder 8 will be lowered when moving toward the web roll W and will be raised when moving in the opposite direction. The sliding blocks 7 also carry ink-distributing rolls 12, which ink the forms on the bed from a suitable fountain 100 (Fig. 6).

In order to move blocks 7, I provide pendulum arms 13 which are slotted as at 13a at their upper ends and slidably engage a fixed rod 14 extending between frames 2 and 3 adjacent the upper portions thereof, substantially centrally of the frames, the lower ends of the arms 13 being mounted upon the ends of the shaft of the impression cylinder 8. Slots 13a permit the arms 13 to move upwardly and downwardly with respect to rod 14 as the arms are rocked.

In order to simultaneously rock arms 13 to reciprocate impression cylinder 8, I provide a shaft 15 journaled in and extending between the frames 2 and 3, shaft 15 carrying on its outer ends relatively large gears 16 which are keyed to shaft 15 so as to rotate therewith. Gears 16 each carry links 17 mounted on eccentric pins 16a adjacent the periphery of gears 16, the opposite ends of links 17 being connected as at 17a with the pendulum arms 13 at points adjacent their centers so that the pendulum arms 13 will be swung on rod 14 as shaft 15 is rotated to reciprocate impression cylinder 8 above the parallel type bed on base 1.

Journaled between frames 2 and 3 below shaft 15 is a drive shaft 18 carrying pinions 19 which mesh directly with gears 16, said shaft 18 also carrying a drive pulley 20 (Fig. 1) which may be operated by a belt 21, and also preferably carrying a fly-wheel (not shown).

Journaled in frames 2 and 3, above shaft 15, are a pair of contacting feed rolls 22 and 23, said rolls carrying at one end gears 22a and 23a (Fig. 1) respectively whereby the feed rolls are caused

to rotate simultaneously at equal speeds but in the opposite direction. Cooperating with upper feed roll 22 is a roll 27 geared to roll 22 and journaled in frames 2 and 3. Feed rolls 22 and 23 are driven from shaft 15 by means of a mutilated gear. As shown more particularly in Figs. 1 and 7, a gear 24 is mounted upon shaft 15 directly below and adapted to mesh with gear 23a on the shaft of feed roll 23, said gear 24 having a cut-out or toothless portion 24a extending throughout half of its periphery, so that when the cut-out 24a comes opposite gear 23a the said gear 23a will cease to be rotated, the cut-out portion 24a being such that the feed rolls 22—23 will not be rotated during the time when impression cylinder 8 is being moved by arms 13 toward the web roll W but gear 24 will rotate the gears 22a and 23a when impression cylinder 8 is moving in the opposite direction, i. e., away from web roll W.

As shown in Figs. 1 and 2, in order to prevent rotation of feed rolls 22, 23 during the time that the cut-out portion 24a of gear 24 is opposite gear 23a, I provide a circular disk 25 mounted upon shaft 15 between frame 2 and the related gear 16, said disk 25 having a cut-out portion 25a extending 180° of the circumference thereof. Cooperating with disk 25 is a disk 26 (Fig. 2) on the shaft of roll 23, said disk 26 having an arcuate recess 26a in its periphery conforming with the curvature of the larger diameter of disk 25, said cut-out 26a being adapted to slide upon the larger diameter of disk 25 during the time that the cut-out portion 24a of gear 24 is opposite gear 23a, the arcuate portion 26a of disk 26 running off the end of the larger diameter of disk 25 at the time that the teeth of gear 24 begin to mesh with the gear 23a, the disk 26 merely rotating on the cut-out portion 25a of disk 25 during the remaining portion of the single revolution of shaft 15.

When the teeth of gear 24 pass beyond gear 23a the disk 26 will be in position shown in Fig. 2 and the cut-out 26a will upon further rotation of shaft 15 slide upon the larger diameter of disk 25.

Thus the feed rolls 22, 23 are rotated during half of each revolution of shaft 15 and are then held by means of the disks 25, 26 against rotation during the remaining half of each revolution, the arrangement being such that the feed rolls 22, 23 are held against rotation during the time that the impression cylinder 8 is moving toward the web roll W, but are positively rotated by shaft 15 when impression cylinder 8 is moving in the opposite direction, i. e., away from web roll W.

Journaled between frames 2—3 adjacent the upper ends thereof is a third feed roll 28, above which is journaled a roll 29 geared to roll 28. Roll 28 is driven directly by feed roll 23, as shown more particularly in Figs. 5 and 6. In Figs. 1 and 5, a sprocket 23b is shown mounted on the roll 23 in alignment with a sprocket 28a of same size mounted on feed roll 28, and a chain 30 runs around sprockets 23b and 28a whereby the rolls 23 and 28 are simultaneously driven at the same speed and in the same direction, roll 28 being of course stationary when roll 23 is stationary. Instead of utilizing the chain and sprocket drive shown in Fig. 5, an alternate drive may be used as shown in Fig. 6 in which a shaft 31 is journaled in bearings 32, 33 and carries a beveled pinion 34 meshing with a beveled gear 35 on the shaft of roll 23, said shaft 31 also carrying a beveled pinion 36 meshing with beveled gear 37 on the shaft of feed roll 28, whereby roll 28 will be driven at the same speed in the same direction as roll 23.

However, any other desired drive for rotating roll 28 by and with roll 23 may be used.

Disposed between frames 1, 2 above feed rolls 28 and 29 is a web guide bar 40; and at the upper front ends of the frames 2, 3 is a supporting bar 41. As shown in Fig. 4 a web-turning bar 42 has one end supported upon an adjustable block 43 disposed at the center of supporting bar 41 and its other end secured as at 42a to the frame 2, said bar 42 being disposed at an angle of 45° to the axis of the press and lying in the horizontal plane of the guide bar 40. Similarly, a web-turning bar 44 has one end supported upon an adjustable block 45 mounted upon supporting bar 41 adjacent the frame 3 and its other end supported by a bracket 46 disposed adjacent the longitudinal axis of the press, said bar 44 being disposed in the horizontal plane of the web guiding bar 40 and being disposed at an angle of 45° to the axis of the press and parallel with the bar 42. As shown, the turning bars 42 and 44 are disposed directly over the type beds and impression cylinder 8, thereby effecting a material saving in necessary size or area of the base 1 of the press so that same may be maintained at a minimum size.

Disposed horizontally on frame 3, adjacent the upper end thereof, is a web-reversing bar 47 which is rotatably mounted in bearings 48 carried by extension arms 49 of frame 3, and bearings 48 being adjustably mounted on extensions 49 and forming a means for effecting register of the impression on one side of the web with those on the other side, the adjustability of rod 47 permitting the effective length of the web in its path through the machine to be varied.

The web from roll W passes into the press under shaft 18, as shown more particularly in Figs. 2 and 5 and then passes upwardly in front of feed rolls 22, 23 and over roll 22 and between rolls 22 and 27, from whence the web passes upwardly and over a guide bar 50 extending between frames 2 and 3, and from thence downwardly in the direction of the arrow w (Fig. 5) and under the impression cylinder 8, from whence the web passes upwardly as at w' and over feed roll 23 and between the feed rolls 23 and 29, the web then passing upwardly and over the guide bar 40. The web then passes horizontally and forwardly as at w2 (Fig. 4) and under the angle bar 42 from whence same passes laterally as at w3 under and over the adjustable web reversing bar 47, from whence the web passes inwardly as at w4 (Fig. 4) under and over the angle turning bar 44 from whence the web passes rearwardly as at w5 over the guide bar 40, from whence the web passes downwardly as shown in Fig. 6 to and between the rolls 28 and 29 and then passes downwardly as at w6 to and under impression cylinder 8, from whence the web passes upwardly at w7 over the bar 50 and downwardly as at w8 between the roll 27 and feed roll 22, the web then passing forwardly in a horizontal direction between the feed rolls 22 and 23, and from thence the web may pass to cutting, folding or other cylinders, as desired.

By the above construction, as drive shaft 18 is continuously rotated, the impression cylinder 8 is reciprocated across the parallel type beds by the pendulum arms 13 which are actuated by gears 16. Owing to the eccentric mounting of the impression cylinder 8, the latter will be lifted above the type beds when moving in a direction away from the web roll W but will be lowered into printing contact with the type beds when

moving in the opposite direction, i. e., towards the web roll W. By reason of the Geneva drive of the feed rolls 22, 23 and 28, same will be driven only when the impression cylinder is moving away from web roll W and will be held against rotation by the disks 25, 26 when the impression cylinder is moving towards the web roll W. Thus when the impression cylinder 8 is moving away from roll W a length of web will be fed from the roll by the feed rolls 22, 23 and 28 to bring an unprinted portion of the web into position for printing, so that when the impression cylinder is moving on the printing stroke towards the web roll W, the stationary web will be printed while the feed rolls 22, 23 and 28 remain stationary.

As the web from roll W passes from the roll over the type bed, one side of the web will be printed, whereupon the web is directed to the turning bars 42 and 44 arranged over the bed and impression cylinder and will be turned over by the arrangement of turning bars and will be re-directed to the other side of the type bed, thus providing a web perfecting unit of simple design and construction, the adjustment of web-turning bar 47 serving to maintain register of the printed portions on both sides of the web.

My flat bed roll-fed web perfecting press will produce the same high quality of printing as any other press in its class, and is so designed that it may be sold within the cost range of the small publisher, since while embodying certain features of flat bed web presses heretofore manufactured the arrangement of parts is such that many idle cams, gears, shafts and other elements are eliminated.

My novel press is moreover so arranged and designed to economize floor space. In my press the pendulum arms pivoted at their upper ends on the frames with their lower ends carrying the journals of the impression cylinder, provide means for moving the impression cylinder to and fro over the bed, and this pendulum construction together with the feature of placing the turning bars 42 and 44 directly above the printing couples reduces the length of the press. Moreover, in my novel pendulum press the type bed is so arranged as to be readily accessible to the operator permitting quick changes or corrections in type forms, and the arrangement is such that efficient inking systems and ink distribution systems may be utilized. In my press a minimum of interchangeable composition rolls are necessary to perfect a 4-page newspaper or an 8-page tabloid publication. Moreover, my press is so designed that it may be shipped completely erected and does not require the provision of a pit at its place of installation.

I do not consider my invention limited to the exact form shown in the drawings, for obviously changes may be made therein within the scope of the claims.

I claim:

1. In a web perfecting printing press having a stationary type bed, and having a travelling impression cylinder cooperating therewith; web turning means disposed directly over the type bed and impression cylinder; a drive web feed roll adjacent the turning means for receiving and advancing the web from the impression cylinder to the turning means before the web is turned over and for receiving and returning the web to the impression cylinder after the web is turned over.

2. In a press as set forth in claim 1, means in the web turning means for registering the areas of impression on the web on opposite sides thereof.

3. In a press as set forth in claim 1, said turning means directing the web to one side of the press; and a web reversing bar at said side of the press, said reversing bar being adjustable to maintain register of the printed areas on both sides of the web.

4. In a web perfecting press having a pair of printing means, web turning means disposed directly above the printing means, and a driven web feed roll adjacent the turning means for receiving and advancing the web from the first printing means to the turning means before the web is turned over and for receiving and returning the web to the second printing means after the web is turned on.

5. In a press as set forth in claim 4, means in the web turning means for registering the areas of impression on the web on opposite sides thereof.

6. In a press as set forth in claim 4, said turning means directing the web to one side of the press; and a web reversing bar at said side of the press, said reversing bar being adjustable towards or from the press to maintain register of the printed areas on both sides of the web.

7. In a web perfecting printing press, a frame, a horizontal stationary type bed therein, a travelling impression cylinder guided in the frame; means for moving the cylinder; means for holding the cylinder off-impression on one stroke thereof and for holding the cylinder on-impression during the other stroke; a pair of web feeding rolls journaled in the frame at one end; intermittent means for rotating the feed rolls while the cylinder is off-impression; a second pair of feed rolls journaled in the frame at the opposite end; means for rotating the second pair of feed rolls with the first pair; web turning means in the frame arranged directly over the type beds respectively; and means for directing the web from the first pair of feed rolls under the cylinder above one side of the bed and to the second pair of feed rolls and to said web turning means; the web being returned from said turning means to the second pair of feed rolls to and under the impression cylinder above the other side of the type bed, and from thence directed out of the press by the first pair of feed rolls.

8. In a press as set forth in claim 7, means in the web turning means for registering the areas of impression on the web on opposite sides thereof.

9. In a press as set forth in claim 7, said intermittent means comprising intermeshing gears on the first pair of feed rolls respectively; a shaft adjacent said rolls, an intermittent gear on said shaft having teeth extending 180° around its periphery and adapted to mesh with one of said intermeshing gears; a disk on said shaft having a cut-out extending 180° around its periphery; a second disk on the feed roll having a peripheral arcuate recess slidably engaging the raised portion of the first disk while the feed roll gear is out of mesh with the teeth of the intermittent gear to prevent rotation of the feed rolls.

10. In a press as set forth in claim 7, said turning means directing the web to one side of the press; and a web reversing bar at said side of the press, said reversing bar being adjustable towards or from the press to maintain register of the printed areas on both sides of the web.

11. In a web perfecting printing press, a frame,

a stationary type bed therein, a travelling impression cylinder guided in the frame; a pair of swingable arms having their upper ends pivoted to the frame and their lower ends engaging the ends of the impression cylinder; means for simultaneously swinging the arms in a pendulum-like motion to move the impression cylinder back and forth above the bed; means for holding the cylinder off-impression on one stroke thereof and for holding the cylinder on-impression during the other stroke; a pair of web feeding rolls journaled in the frame at one end; intermittent means for rotating the feed rolls while the cylinder is off-impression; a second pair of feed rolls journaled in the frame at the opposite end; means for rotating the second pair of feed rolls with the first pair; web turning means in the frame arranged directly over the type bed respectively; and means for directing the web from the first pair of feed rolls under the cylinder and above the bed at one side of the press, the web passing to the second pair of feed rolls to advance the web to the turning means, and the web being returned from said turning means to the second pair of feed rolls to and under the impression cylinder above the type bed at the opposite side of the press and from thence directed out of the press by the first pair of feed rolls.

12. In a press as set forth in claim 11, means in the turning means for registering the areas of impression on the web on opposite sides thereof.

13. In a press as set forth in claim 11, said turning means directing the web to one side of the press; and a web reversing bar at said side of the press, said reversing bar being adjustable towards or from the press to maintain register of the printed areas on both sides of the web.

14. In a press as set forth in claim 11, said arm swinging means comprising a driven shaft journaled in the frame; a second shaft journaled in the frame; gears on the second shaft opposite said arms; pinions on the driven shaft meshing with said gears; and links connecting eccentric pins on the gears with said arms adjacent their mid points.

15. In a press as set forth in claim 11, said intermittent means comprising intermeshing gears on the first pair of feed rolls respectively; a shaft adjacent said rolls, an intermittent gear on said shaft having teeth extending 180° around its periphery and adapted to mesh with one of said intermeshing gears; a disk on said shaft having a cut-out extending 180° around its periphery; a second disk on the feed roll having a peripheral arcuate recess slidably engaging the raised portion of the first disk while the feed roll gear is out of mesh with the teeth of the intermittent gear to prevent rotation of the feed rolls.
